Primary Examiner—James R. Laren**Attorney, Agent, or Firm**—Herbert Dubno**[57] CLAIM**

The ornamental design for a combined hand shower holder and plumbing connector, as shown.

DESCRIPTION

FIG. 1 is a perspective view showing the front, right side, and top of a combined hand shower holder and plumbing connector embodying my new design;
 FIG. 2 is a left-side elevational view thereof;
 FIG. 3 is a bottom view thereof;
 FIG. 4 is a front view thereof;
 FIG. 5 is a right-side elevational view thereof;
 FIG. 6 is a top view thereof; and,
 FIG. 7 is a rear view thereof.

FIG.1

FIG. 2

FIG. 3

FIG. 4

FIG. 5

FIG. 6

FIG. 7
